GUN

Philip I. Bowman, Syracuse, N. Y.

Application September 2, 1955, Serial No. 37,755

Term of patent 14 years

(Cl. D30—1)

The figure is a side elevational view of a gun, embodying my new design.

The opposite side of the gun is the same as the side shown.

I claim:

The ornamental design for a gun, as shown and described.
